(57) CLAIM

The ornamental design for a table, as shown and described.

DESCRIPTION

FIG. 1 is a rear-right perspective view of a table that incorporates our new design.

FIG. 2 is a top view thereof.

FIG. 3 is a rear view thereof.

FIG. 4 is a front view thereof

FIG. 5 is a left-side view thereof. The right-side view is a mirror image of the left-side view; and,

FIG. 6 is a bottom view thereof.

The broken line showing of the table feet is for illustrative purposes only and forms no part of the claimed design.
